UNITED STATES PATENT OFFICE.

GEORGE EDWARD MACONNELL, OF REDSTONE, MONTANA.

TRY-SQUARE HANDLE.

1,369,038.

Specification of Letters Patent. Patented Feb. 22, 1921.

Application filed October 22, 1919. Serial No. 332,368.

To all whom it may concern:

Be it known that I, GEORGE EDWARD MACONNELL, a citizen of the United States, and a resident of Redstone, in the county of 5 Sheridan and State of Montana, have invented certain new and useful Improvements in Try-Square Handles, of which the following is a specification.

My invention is an improvement in try- 10 square handles, and has for its object to provide a handle of the character specified wherein the said handle is rabbeted on one face to be flush with the face of the try-square for permitting mortises to be 15 marked easily and expeditiously.

In the drawings:

Figure 1 is a top plan view of the im- 20 proved square;

Fig. 2 is an end view, looking at the end 25 of the handle remote from the blade;

Fig. 3 is an end view, looking at the op- 30 posite end;

Fig. 4 is a view looking at the edge of 35 the handle.

In the present embodiment of the invention the try-square comprises a blade 1 of metal or the like and a handle 2 of wood. This handle has at one end a mortise in which is received one end of the blade, and 40 the blade is connected to the handle by means of rivets 3. At one face of the try-square and at the inner side edge of the handle it is rabbeted from end to end, to form a shoulder 4 and a surface 5 at right 45 angles to the shoulder and flush with the adjacent face of the blade.

Referring to Fig. 1, it will be seen that the width of the rabbeted surface is slightly greater than half the width of the handle,

and in the present instance this rabbeted 40 surface is an inch in width. Upon the end of the handle remote from the blade, and on that portion of the end adjacent to the rabbeted surface, there is provided a scale 45 6, one inch in length, and suitably grad- 50 uated, and that side edge of the handle adjacent to the blade is also provided with a scale indicated at 7.

Thus it will be evident that two shoulders 55 are provided for engaging the edge of the object upon which the blade is to be used, namely, that shoulder 4 formed by the rab- 55 bet, and that shoulder 8 at the opposite side of the blade, that is, the inner side edge of the handle.

The use of the improved blade will be evident from the description. Either shoulder 4 or 8 may be engaged with the edge of the work, as indicated in Fig. 2, and the blade extends perpendicularly to the 60 long axis of the work, lying upon the sur- 65 face thereof.

I claim:

A try-square comprising a handle and a single blade secured thereto with its sides 65 in parallel relation to the planes of the handle and at right angles thereto, the blade extending entirely across one end of the handle and being graduated, and the edge 70 of the handle toward the blade being cut away or rabbeted to define a surface flush with one side of the blade and a right an- 75 gular shoulder extending the full length of the handle, the portion of the blade be- 75 tween the inner edge of the handle and the shoulder being also graduated.

GEORGE EDWARD MACONNELL.
